JOHN B. GOLDSBOROUGH, OF CROTON, NEW YORK.

INTERLOCKING METAL SHEETING.

1,090,911.

Specification of Letters Patent. Patented Mar. 24, 1914.

Application filed August 29, 1912. Serial No. 717,726.

To all whom it may concern:

Be it known that I, JOHN B. GOLDSBOROUGH, a citizen of the United States, residing at Croton, in the county of Westchester 5 and State of New York, have invented certain new and useful Improvements in Interlocking Metal Sheeting, of which the following is a specification.

My invention relates to a metal sheeting 10 or sheet piling of the class of rolled metal piling formed in sections, wherein the several sections are capable of relative longitudinal movement, and permitting lateral deflection of several sheet piles of a series 15 when connected.

The principal object of my invention is 20 to provide an integral sheet metal piling section which may be rolled to form the interlocking edges, so that when placed in engagement with an adjacent section said interlocking edges will form a grip or interlocking joint capable of resisting the various strains that may come upon it, and that 25 the interlocking edges will form a water-resisting joint.

A further and important object of my invention is to provide a construction wherein 30 in the interlocking of the adjacent sections may be made by a lateral entrance or engagement of the said edges, and without placing the said adjacent piling sections end to end, whereby it is possible to set up a line of sheet piles in position to drive from the walls of a trench where there is head- 35 room but slightly exceeding the length of the sheet metal sections, and this advantage is accomplished by the side entrance rather than the end to end engagement.

Previous structures in the class of interlocking sheet metal piling known to me have 40 been assembled by an end to end engagement. It is customary to assemble the sections to form the walls of a pit or trench upon the surface where the proposed excavation is to be made, and this for the reason that in driving the sections they will guide one another and will be prevented from being deflected. It will be seen therefore that head-room is required to assemble 45 the said sheet piling, more than twice the length of the sheet piling, for the reason that one section must be placed upon the ground, and the adjacent section must be raised above it to double its height, so that 50 engagement may take place, and in setting

up a line of 20 feet of sheet piling, which is an ordinary length, where such interlocking is accomplished by the end to end engagement, an apparatus, 40 feet high, such as a derrick, must be provided to raise the 55 sheet piling so that it may engage the end of the adjacent section. A scaffolding or other like means must be provided for workmen to stand on, so that they may guide the lower end of the sheet piling section held in 60 suspension by the derrick into proper engagement. Unless this is a loose fitting engagement, even though all the appliances described have been provided, great difficulty will be experienced in sliding or lowering the suspended member into position. 65 Frequently the sections bind, requiring force to keep the sections in their proper position. This must be applied in the form of a pull at the bottom or a push at the top of the suspended member. Either force is so difficult to apply in the places in which such sheet piling is frequently assembled, as for 70 instance beneath the foundation of a building, that it is easier to make such a joint 75 a free fitting or loose joint depending upon accidental contact of the material and the filling of the space within the joint with earth to make it tight. It will be perceived therefore that by the methods of assembling 80 sheet piling requiring end to end engagement, a considerable head-room is essential, and this is usually difficult to obtain. For instance in connection with subway excavations 85 in large cities which are now of increasing importance, the excavation often extends to great depths through soil of varying character from dry running sand, soft clays, water-bearing soils, and quick-sands. It is necessary that the foundations of the 90 commercial buildings which usually line the routes of such subways shall be thoroughly protected, and that the sheeting driven to hold the soil in place under these heavy 95 walls shall be of a form and character that will make strong water-tight walls of great strength capable of preventing the flow of water into the excavation, of maintaining the material on which the weights of the 100 buildings rest, and of resisting the lateral pressure due to the weight of this material, and the superimposed loads of the buildings. The sheeting, to accomplish this, must be set up in place ready for driving where 105 there is scarcely room to stand a single sec- 110

tion upright. It will be perceived that under such conditions end engagements previous to driving are practically impossible. It is likewise practically impossible to drive one section and then engage it by another section and drive a second section down later, as obstructions which are met with tend to deflect one or the other section from its proper line.

10 It will be seen from the foregoing that by the use of end to end engagements it is difficult if not impossible to obtain a satisfactory water-tight joint. It is practically necessary that all sections should be set up in advance 15 of the driving, and that during the driving one section should not be driven substantially in advance of the other. If one were driven greatly in advance of the other some slight obstruction might deflect it from its proper 20 line. This deflection would be increased when the next section was driven, and would keep increasing until the deflection would become such as to destroy the entire usefulness of the piling. It is therefore necessary 25 that all the sheets be set up together, and that the bottom of each sheet be driven but slightly in advance of the one adjoining it. In this way all the sheet piles forming an interlocking wall, if driven simultaneously 30 or so as to maintain but a slight variation in the penetration of the piles, employ the interlocking qualities to the best advantage, and each one will maintain its relative position even though they encounter obstructions 35 that would easily deflect them if they were being driven separately. When such sheet piles are driven altogether, they form an integral line capable of resisting and pushing through or aside obstructions, and 40 maintaining their position to form a straight and impervious wall. It will therefore be perceived that for purposes of safety where it is necessary to form a pit in such location it is practically necessary that the sections 45 should be interlocked before they are driven. It is further apparent that in deep excavations in or adjacent to the foundations of buildings, sufficient head-room may not be obtained to drive sheet piles by an end to 50 end engagement. Under such circumstances my invention may be used with great advantages and with remarkable efficiency.

The sheet piling is simple to produce and easy to assemble. No more head-room is required than the length of the sheet piling section and a space for the driving means. The lateral engagement which permits this also provides for an interlocking joint, which is substantially water-tight, which has engagement throughout its length, and not at isolated portions.

My improved sheet piling interlocks the sections so that one section will not be deflected from position relative to the adjacent section.

A sheet piling of the character described when used for the purpose of maintaining the sides of an excavation for the purpose of building masonry walls within the lines of the excavation, is often removed when the masonry has been completed. The side entrance sheet piling according to my invention provides a quick release and can be more easily withdrawn.

Desirable forms in which my invention 75 may be embodied are illustrated in the accompanying drawings, wherein—

Figure 1 is a partial elevation of assembled sheet piling sections located vertically; Fig. 2 is a top view of the sheet piling of Fig. 1 illustrating the interlocking; Fig. 3 is another and the preferred form of constructing the said sheet piling; Fig. 4 is a plan view of piling similar to that illustrated in Fig. 3 showing however a 80 different manner of placing interlocking edges; Fig. 5 illustrates a plan view of the piling of Fig. 3 showing however still another manner of locating the interlocking edges; Fig. 6 is an elevation of the sheet 85 piling illustrated in Fig. 3.

According to my invention the sheet piling is preferably rolled from sheet metal, such as sheet steel, and comprises a body A and interlocking ends B C. The said interlocking ends are preferably produced by rolling, although they may be produced in other ways. Such interlocking ends may be integral with the body, as illustrated in Fig. 3, or portions thereof may be formed separately and attached thereto, as illustrated at F¹ in Fig. 2.

The interlocking joint comprises corresponding interlocking flanges D E which are illustrated as substantially perpendicular to the bodies A, and as being formed upon the longitudinal edges thereof by being upset. Retaining hooks F are provided, and the ends of such hooks point inwardly or toward the ends of the hooks or flanges E. The ends of hooks F are situated preferably outside of the ends of hooks E a sufficient distance to permit the entrance of the interlocking flange D. The ends of the said hooks may without injury be separated a greater distance than the width of the said flange. Preferably the inner surface of the retaining hook F is curved to correspond to the arc of movement of the interlocking flange D when the sections are assembled.

The said flange E and retaining hook F enclose a space or channel G which receives the interlocking flange D. In Fig. 4 is shown the manner of entering the said interlocking members for assembling. Here the flange D is located so that its connected body A is substantially perpendicular to the outer face of the locking flange E. In this position the end a of the body A will enter within the entrance to the channel G, and as the casing 120 125 130

section is swung or turned the flange D is swung around until it is behind the locking flange E, whereupon the abutting faces of the said two flanges will hold the interlocking sheet piling sections against relative longitudinal movement. In this position a plurality of points of contact will be provided. As seen in Fig. 4, four such points of contact exist with the construction there illustrated, and these are designated respectively H, I, J and K and are located as follows:—H occurs between the end of the retaining hook F and the body of the interlocking section; I occurs between the curved inner surface of the said retaining hook F and the end *a* of the interlocking section; J occurs between the end of the locking flange E and the interlocking body A; and K occurs between the inner faces of the locking flanges D E. By means of the said points of contact a tight joint is produced between the interlocked casing sections, and leakage of water is prevented. Furthermore at the point H the end of the retaining hook F abuts against the body A of the interlocked section, and a similar engagement will occur between the ends of either the hooks D or E and the other section, whereby a stop is provided for preventing relative lateral movement of the sheet metal piling sections.

It is not essential that the retaining hook F should be integral with the body A, as illustrated in Fig. 3, although this is preferred. If desired the said retaining hook may be formed separately and secured to the said body A, as shown in Fig. 2 at F¹, where said retaining hook is a separate piece and is attached as by rivets L. Furthermore, although I have illustrated in Figs. 3, 4 and 5 the hook E as being offset from the body A by a return bend whereby the bottom of said hook is offset from the body A, this construction is not essential, as a satisfactory lock may be produced by simply upending the locking flange without causing the same to be offset on both sides of the body A, as seen at E¹ Fig. 2.

The preferred construction contemplates that the hooks E F shall be at one end of one section and the hook D at the other end of the said section, but this is not necessary, as seen for instance in Fig. 4, where one section has two hooks D one on either side, and the adjacent section has on each side hooks E F. This may be preferred for some uses. Furthermore, although I have illustrated in Fig. 4 that the interlocking flanges D project from the same side of the body A, this is not essential, as these hooks may project from opposite sides, as seen in Fig. 5, and this form may have advantages in assembling, enabling the sections to be assembled from opposite sides.

In the employment of my present inven-

tion the interlocking sections are engaged by first placing one section on end in the position in which it is to be driven, and the adjacent section to be interlocked with it is placed alongside but at right angles to the line of the first section. The flange D is then entered above the flange E, and the engagement is accomplished by a revolving movement wherein the section so placed at right angles is swung about the end of the hook E as an axis and turned to locking position, as seen in Fig. 4. The shape of the interlocking members is such that this turning is easily accomplished without undue friction or binding, while when in assembled position the interlocked hooks rest firmly in contact with one another for the full length of the sheet metal piling section.

It will be observed that in sheet metal piling construction according to this invention, a lateral pressure only serves to increase the contact between interlocked sections and thereby to increase the strength and the ability to resist the inflow of water. The shape of the interlocking joints may be suitably varied to permit of a corner joint, so that sections may be assembled at right angles, or the body A may be bent if desired.

It has been heretofore stated that in the specific construction illustrated four points of contact are provided, and that the contact extends the entire length of the joint in a vertical direction. While the sheeting might be so placed that one or more of these points of contact might separate, they could not all separate at the same time. Therefore any amount of disturbance during or after driving could not so separate all the points of contact of the interlocking joint in such a way as to give a free opening for the liberal flow of water through the joint. This form of metal sheet piling can be used and placed in a horizontal position not only for the purpose described, but for any other purposes where such sheet piling is required, as for instance for a well, a foundation pit, a mine shaft, or other like excavation where a stronger or more permanent sheeting than wood might be required.

I have illustrated and described sheet piling as employed with the joints in a vertical position, but it will be apparent to those skilled in the art that the said sectional sheet piling may advantageously be employed by assembling the same in a horizontal position. For such use the top or curb piece must be securely held in position, whereupon the succeeding members are hung to it by assembling in the manner hereinbefore described. Such succeeding members are securely retained in place and cannot get loose and fall out, for the reason that in order to disengage them the bottom section must be first disengaged by swinging the lower edge of the piece to be disengaged

up until it is at right angles to the side, then it can be removed in the same way in which it was put together. In other words, a horizontal sheeting of a pit hangs like a curtain from the top. It will be apparent that the side engagement of interlocking sheeting is the only practical interlocking sheeting that could be used in a horizontal position as a lining for an excavation such 10 as described above.

I have illustrated a few of the shapes in which an integral rolled beam may be made in accordance with my invention, but it is evident that such beam could be rolled in other shapes whether integral or in sections joined together, and it is evident that modifications can be made in the particular shapes illustrated, and other forms employed, without departing from my invention as defined in the accompanying claims. 15 20

I claim as my invention:—

1. Sheet metal piling formed in sections and having longitudinal interlocking edges comprising a flange on the edge of one section, and hooks on the edge of the adjacent section, said flange being substantially perpendicular to the face of its section, and said hooks having their ends separated forming a side entrance for said flange. 25
2. Sheet metal piling formed in sections having longitudinal interlocking edges and adapted to interlock by a lateral entrance, said interlocking edges comprising a substantially rectangular flange on the edge of one section and a corresponding rectangular flange on the edge of the adjacent section, and a retaining hook on said adjacent section having its edge projecting inwardly and situated outside of said flange a distance substantially equal to the thickness of the interlocking flange, and having its inner surface curved forming an entrance and guiding channel for said interlocking flange, whereby a plurality of points of con- 30 35 40

tact between said interlocking edges is obtained and a tight joint is provided.

3. Sheet metal piling formed in sections having longitudinal interlocking edges and adapted to interlock by a lateral entrance, said interlocking edges comprising a substantially rectangular flange on the edge of one section and a corresponding rectangular flange on the edge of the adjacent section, and a retaining hook integral with said adjacent section having its edge projecting inwardly and situated outside of said flange a distance substantially equal to the thickness of the interlocking flange, and having its inner surface curved forming an entrance and guiding channel for said interlocking flange, whereby a plurality of points of contact between said interlocking edges is obtained and a tight joint is provided. 50 55 60

4. Sheet metal piling formed in sections and having longitudinal interlocking edges, 65 said interlocking edges adapted to engage by a lateral entrance and providing a plurality of points of contact between said interlocking edges.

5. Sheet metal piling formed in sections 70 and having longitudinal interlocking edges, said interlocking edges adapted to engage by a lateral entrance and providing a plurality of points of contact between said interlocking edges throughout the length 75 thereof.

6. Sheet metal piling formed in sections and having longitudinal interlocking edges, said interlocking edges adapted to engage by a lateral entrance and providing four points 80 of contact between said interlocking edges.

In witness whereof, I have hereunto signed my name in the presence of two subscribing witnesses.

JOHN B. GOLDSBOROUGH.
